UNITED STATES PATENT OFFICE.

HAROLD I. ADAMS, OF WAREHOUSE POINT, CONNECTICUT, ASSIGNOR TO THE BILLINGS & SPENCER COMPANY, OF HARTFORD, CONNECTICUT, A CORPORATION OF CONNECTICUT.

HAND TOOL.

1,413,698.

Specification of Letters Patent. Patented Apr. 25, 1922.

Application filed March 3, 1921. Serial No. 449,473.

To all whom it may concern:

Be it known that I, HAROLD I. ADAMS, a citizen of the United States, and a resident of Warehouse Point, in the county of Hartford, State of Connecticut, have invented 5 certain new and useful Improvements in a Hand Tool, of which the following is a specification.

The aim of the present invention is to provide a hand-tool having various features of 10 novelty and advantage. In accordance with the present invention, the tool has a cross handle adapted to be folded down along side of the tool shank or stem for compactness 15 and convenience in carrying it around, but complete withdrawal or removal of the handle is prevented so that loss or displacement of the parts is entirely avoided. The handle is of simple, integral construction, 20 may be cheaply manufactured, and is adapted to be readily brought into operative or folded down positions. The invention is also concerned with the manner in which a member is held in the socket of the tool.

25 In the accompanying drawing: Figure 1 is a side view, partly in section, of my improved tool, the handle being shown by full lines in folded down position and by dotted lines in operative position, and

30 Fig. 2 is an edge view of the retaining clip.

Referring to the drawings in detail, *a* is a tool body or shank having a transverse aperture *b* at one end through which extends the 35 cross handle *c*. In the present instance, I have shown the operating end of the shank in the form of a socket *d* adapted to receive a member, such, for instance, as the squared shank of a nut wrench *e*, shown in 40 dotted lines in the drawing. It is to be understood, however, that this disclosure is by way of illustration only, it being evident that the invention may be applied to tools of various kinds and types.

45 The handle *c* is preferably formed from a single metal rod of such diameter as to have a sliding fit in the aperture *b*. One end of the handle is of reduced diameter and is bent or curved outwardly as at 12, 50 and then bent inwardly to form a hook 13. It will be seen that when the curved portion 12 is within the aperture *b*, the handle may be swung from one to the other of the

positions shown. The hook is of such size and shape as to constitute a projection which 55 prevents withdrawal of the handle. If desired, the other end of the handle may have a head 14.

For the purpose of frictionally holding shanks and the like within the socket *d*, the 60 latter is provided with a spring clip *f*. This clip is formed of a resilient strip of metal bent back upon itself to form a pair of arms 15, 16, which straddle the wall of the socket, as shown. It will be seen that the socket is 65 apertured as at 17 to accommodate the clip. The arm 15, which may lie within a groove 18 of a socket, is bowed outwardly intermediate its ends to resiliently press against the wrench shank. Preferably, one of the 70 arms is bent inwardly to form an offset 19 which engages against the edge of the aperture 17 and spaces the closed end of the clip from that edge.

It is, of course, obvious that my invention 75 is susceptible of various modifications and changes which are within the spirit of the invention without departing from the scope of the following claims, it being understood that the present disclosure of my invention 80 is by way of illustration only and it is not to be taken as restrictive of my conception.

I claim as my invention:—

1. A tool shank having a transverse aperture; and a handle comprising a rod of substantially the same diameter as said aperture and adapted to slidably fit therein and having a portion of reduced diameter in all directions with a reverse bend so as to permit the folding of the handle along side said tool shank and prevent withdrawal of the handle from said aperture.

2. A tool shank having a transverse aperture of substantially uniform diameter throughout; and a handle slidable within 95 said aperture and having a portion of reduced diameter in all directions bent to permit the handle to be folded down along side of said shank, and a projection on the end of said bent portion for preventing complete 100 withdrawal of the handle from said aperture.

3. A tool shank having a transverse aperture; and a handle slidable within said aperture and having a portion bent at an angle 105 to the length of the handle, said handle be-

ing of reduced diameter in the direction of bend to permit the latter to be folded down along side of the shank, the free end of said reduced portion being of hooked shape to prevent complete withdrawal of the handle from said aperture.

4. A tool shank having a transverse aper-

ture; a handle slidable fitting therein and comprising a rod having an integral reduced end provided with a double bend for 10 permitting the handle to be folded down along side of the shank while preventing complete withdrawal of the handle.

HAROLD I. ADAMS.
